(57) **CLAIM**

The ornamental design for a dog training transmitter, as shown and described.

DESCRIPTION

FIG. 1 is a front, right and top perspective view of a dog training transmitter, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is an enlarged view of portion of FIG. 1 thereof.
The broken lines shown in the drawings illustrate portions of the dog training transmitter that form no part of the claimed design.
The dot-dash broken lines depict the boundaries of the enlargements that form no part of the claimed design.
